GAME WITH BALL-OPERATED GATES

Peter J. Ragusin, Tinley Park, Ill.

Application January 18, 1951, Serial No. 206,635

6 Claims. (Cl. 273—118)

1

This invention relates to games, and has for one of its main objects the provision of a simple and improved game which will afford considerable amusement for the player.

Another object of the invention is to provide a game which requires introduction of movable objects into a game-board in certain order to achieve the desired results.

Another object of the invention is to provide a game comprising, in combination, a plurality of movable objects, a game-board having a first inlet for receiving at least one of the objects and an outlet for discharging said object, a runway for delivering the object received by the first inlet to the outlet, a plurality of gates disposed at spaced locations along the runway for successive engagement by the object received by the first inlet, additional inlets for receiving the other objects, and means actuated by the introduction of the other objects into the additional inlets for actuating the gates to advance the object received by the first inlet to a succeeding gate when said object is in engagement with the gate.

Another object of the invention is to provide a game of the class described wherein there are pivots on which the gates are carried for swinging movement and wherein the means for actuating the first-mentioned gates comprises additional gates carried by the pivots for turning the pivots and the first gates by the other objects received by the additional inlets.

Another object of the invention is to provide a game of simple and inexpensive construction which is composed of few parts and adapted for convenient assembly, and to operate effectively for the desired purpose.

Further features and advantages of the invention will be apparent from the following detailed description and the accompanying drawing.

In the drawing:

Figure 1 is a perspective view of one form of game embodying the present invention;

Figure 2 is a longitudinal sectional view taken on the line 2—2 of Figure 1;

Figure 3 is a longitudinal sectional view taken on the line 3—3 of Figure 1;

Figure 4 is a transverse sectional view taken on the line 4—4 of Figure 2; and

Figure 5 shows the five movable objects or ball members for the particular game selected for illustration.

Referring now to the drawing, the game selected for illustration comprises a game-board 1

2

of box-like form having a top wall 2, a bottom wall 3, front wall 4, rear wall 5, and end walls 6 and 7.

The hollow interior of the game-board 1 is divided longitudinally by an upright wall or partition 8 disposed upright between the top and bottom walls 2 and 3 and extending longitudinally between the end walls 6 and 7.

The walls of the game-board 1 may be formed of wood, fiber board, plastic material, cardboard, heavy paper-like material, or any other suitable or preferred material. The bottom wall 3 is preferably hinged at 9 to the rear wall 5 for a purpose which will presently appear. A catch 10, or other suitable means, may be provided for releasably securing the bottom wall in closed position, or this may be accomplished in any other suitable or preferred manner.

The bottom wall 3, between the front wall 4 and the partition 8, constitutes a runway 11 which, in use, is preferably disposed to decline downwardly slightly from the end wall 6 to the end wall 7. The top wall 2 has a first inlet opening 12 for receiving at least one of a plurality of movable objects 13. Figure 5 shows five movable objects 13 for the particular embodiment of the invention selected for illustration, each in the form of a ball member of rubber or any other suitable material.

The end wall 7 has an outlet opening 14 opening from the end of the runway 11 for discharging from the game-board the object received by the first inlet 12. The inlet 12 is surmounted by an upright tube 15 through which one of the ball members 13 may be conveniently introduced to pass through the inlet 12. The outlet 14 has an outlet tube 16.

A plurality of gates 17 are disposed at spaced locations along the path of the runway 11 for successive engagement with the object 13 introduced through the first inlet 12. The gates 17 are carried for swinging movement by pivot pins 18 which extend transversely through the spaces on opposite sides of the partition 8, and are mounted for turning movement, for example, in the front and rear walls 4 and 5 and in the partition 8. The gates 17 are of generally bell-crank form, and each has an arm 17a normally disposed in generally horizontal position, and another arm 17b normally disposed in generally vertical position as shown in Figure 3.

The game-board has a plurality of additional inlet openings 19, one for receiving each of the four ball members 13 other than the one which is introduced through the first inlet 12. The inlet

openings 19 are spaced longitudinally and open into the space between the partition 8 and the rear wall 5. Transverse partitions 20 are positioned across the space between the partition 8 and the rear wall 5 and to the left of each inlet 19 as the device is shown in Figure 2. Each additional inlet 19 is surmounted by an upright tube 21 through which one of the ball members 13 may be conveniently introduced to drop through the adjacent inlet 19.

An additional or second gate 22 is carried by each pivot pin 18 in position between the partition 8 and the rear wall. The additional or second gates 22 are of generally bell-crank form, and each has an arm 22a normally disposed in generally horizontal position beneath the adjacent inlet 19 and another arm 22b normally disposed in generally vertical position as shown in Figure 2. The lower ends of the arms 22b are weighted at 23 normally to retain the gates 22 in the positions shown in Figure 2, and the gates 17 in the positions shown in Figure 3, and to return the respective gates to these positions. Spring means or other suitable means may be employed to retain the gates in their normal position and to return them to such positions in lieu of the weights 23 if desired.

To operate the game, one of the ball members 13 is dropped into the tube 15 and drops through the inlet 12 and onto the runway 11 and rolls downwardly to the right (Figure 3) into engagement with the depending arm 17b of the first gate 17. The effort exerted by ball 13 on gate 17 is not sufficient to rotate the gate about pivot 18 in opposition to the weight 23 on gate 22. The object of the game is therefore, to successively raise the gates 17 and to pass this ball along the runway 11 and to discharge the same through the outlet tube 16 by the introduction of the other four balls 13 into the tubes 21.

Now in order to accomplish this result, it is necessary to introduce the first of the other four balls 13 into the tube 21 at the left as the device is shown in Figures 1 and 2; thereafter the next of the remaining three balls 13 into the next tube 21 to the right; thereafter the next of the remaining two balls 13 into the next tube 21 to the right; and thereafter the last ball 13 into the tube 21 at the right hand end of the device.

As the first of the four other balls 13 is introduced through the inlet at the left, it drops onto the arm 22a of the gate 22 at the left. The combined effort of the ball 13 on arm 22a of gate 22 and of ball 13 on arm 17b of gate 17 swings both gates about common pivot 18 in a counter-clockwise direction. This swinging of the gate 17 on the first pivot 18 counterclockwise advances the ball 13 from the first gate 17 to the second gate. Introduction of the remaining three balls 13 into the respective tubes 21 successively swings the other gates 17 in like manner successively to advance the first ball which is introduced through the inlet 12 to these gates 17, and finally out through the outlet 14 and discharge tube 16.

The number of gates and inlets, and the construction and combination of the various parts of the device may vary widely within the scope of the present invention.

Ball members 13, introduced into the game-board of the device through the various inlet openings, may be removed by the simple expedient

of unlatching the bottom wall 3 and swinging it downwardly to open position about the hinge 9.

The embodiment of the invention shown in the drawing is for illustrative purposes only, and it is to be expressly understood that said drawing and the accompanying specification are not to be construed as a definition of the limits or scope of the invention, reference being had to the appended claims for that purpose.

10 I claim:

1. In a game, in combination, a plurality of movable objects, a game-board having a first inlet for receiving at least one of said objects and an outlet for discharging said object, said game-board comprising a box-like structure having a central longitudinal partition defining a runway on one side of said partition for delivering the object received by said first inlet to said outlet, a plurality of transverse longitudinally spaced apart partitions on the other side of said longitudinal partition defining a plurality of compartments, a plurality of first gates disposed at spaced locations along said runway for successive engagement by the object received by said first inlet, pivots on which said first gates are carried for swinging movement, the effort exerted by the object received by said first inlet on said first gates being insufficient to turn said first gates to clear said object, said game board having a plurality of additional inlets one each opening into each of said plurality of compartments for receiving the other objects, and additional gates one each positioned in said plurality of compartments and carried by the same pivots of said first gates for turning said pivots and said first gates by the combined effort of the object received by said first inlet on said first gates and of the objects received by said additional inlets on said additional gates to advance the object received by said first inlet to a succeeding gate when said object is in engagement with the actuated gate.

2. A game according to claim 1 wherein there is means operable to remove the other objects received by said additional inlets from the game-board.

3. A game according to claim 1 wherein there is a hinged bottom for said box-like structure for removing the other objects received by the additional inlets from the game board.

4. A game according to claim 1 wherein the additional gates are of generally bell-crank form.

5. A game according to claim 1 wherein the first inlet and the additional inlets have upstanding tubes surrounding said inlets and fixed to and projecting upwardly from said box-like structure.

6. A game according to claim 1 wherein the bottom of the runway is declined downwardly from the first inlet to the outlet.

60 PETER J. RAGUSIN.
